UNITED STATES PATENT OFFICE

128,137

DESIGN FOR A FUNERAL SERVICE CHAPEL

Alvin H. Gruber, Highland Park, Mich.

Application September 26, 1940, Serial No. 95,404

Term of patent 7 years

To all whom it may concern:

Be it known that I, Alvin H. Gruber, a citizen of the United States, residing at Highland Park, in the county of Wayne and State of Michigan, have invented a new, original, and ornamental Design for a Funeral Service Chapel, of which the following is a specification, reference being had to the accompanying drawing, forming part thereof, in which:

Figure 1 is a front perspective view of a funeral service chapel showing my new design; and

The end of the building not shown is the same as the end shown at the right of Figure 1.

I claim:

The ornamental design for a funeral service chapel, substantially as shown and described.

ALVIN H. GRUBER,
